[57] CLAIM

The ornamental design for a programmable logic controller, as shown and described.

DESCRIPTION

FIG. 1 is a top, front and left side perspective view of programmable logic controller showing my new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof; and,
FIG. 8 is a bottom, rear and right side perspective view thereof.
